UNITED STATES PATENT OFFICE.

NORMAN E. DONOHUE, OF CAMBRIDGE, OHIO.

SAFE LOCK.

Application filed April 2, 1923. Serial No. 629,391.

To all whom it may concern:

Be it known that I, NORMAN E. DONOHUE, a citizen of the United States, residing at Cambridge, in the county of Guernsey and 5 State of Ohio, have invented certain new and useful Improvements in Safe Locks, of which the following is a specification.

My invention relates to improvements in safes, and has particular reference to a device 10 in the nature of an attachment, whereby the lock may be located at a point remote from the spindle, and be operated thereby, but being safe from injury or removal, by the driving-in of the spindle, as it 15 is a practice by burglars, in the opening of safes.

An important object of the invention is to provide an attachment of the above mentioned character, which is of extremely simple 20 construction, and which is designed for use in connection with the lock found upon the ordinary safe door, without materially altering the construction of the lock, or other parts of the safe.

25 The usual method employed in breaking into safes, is to first break off the lock dial. The spindle is then driven out of its operative position into the safe. In the ordinary safe, this driving-in of the broken spindle, 30 takes the lock off with it, whereby the door may be readily opened. In some safes, the door will not open, when the lock is broken in this manner, as the safes are equipped with a lock dog, which would lock the safe 35 closed. But this is readily overcome, by reaching through the spindle hole, with a piece of wire or the like, and tripping the lock dog, whereby the safe is readily opened.

In accordance with my invention I provide 40 a support for the lock which is ordinarily mounted upon or in proximity to the spindle of the safe. This support is separate from and detachable with the inner side of the safe door and may be located at any remote point from the spindle. It is preferred that the distance be considerable, and the distance may be varied in connection with each particular safe, if desired. A support is provided for a shaft which is geared 45 to the tumblers and also geared to the spindle. As a result of this, the same tumbler lock which is furnished with the ordinary safe, may be thus located upon the safe door at a point remote from the spindle, without 50 in any way materially changing the construction of the lock, or other parts of the

safe. The arrangement is advantageous inasmuch as the driving-in of the spindle can in no way drive off the lock or injure the same, and when the spindle is thus driven-in, 60 it is virtually impossible to operate the lock, for manipulating the tumblers. It is certainly more difficult than operating the tumblers from the usual lock dial. Further, by placing the lock at a point remote from the 65 spindle and driving from the spindle through the medium of gearing, the feeling of the operation of the tumblers, as they pick up, by the so-called "finger artist" is impossible. 70

Other objects and advantages of the invention will be apparent during the course of the following description.

In the accompanying drawings forming a part of this specification, and in which like numerals are employed to designate like parts throughout the same,

Figure 1 is a fragmentary side elevation of a safe door, from the outer side, and,

Figure 2 is a longitudinal section taken 80 on line 2—2 of Figure 1.

In the drawings, wherein for the purpose of illustration is shown a preferred embodiment of my invention, the numeral 5 designates a safe door, which may be formed of inner and outer metal plates 6 and 7, with the usual fire proof lining 8. A sleeve 9 is formed integral with the outer plate 7, for pivotally receiving the spindle 10 of the usual lock. This spindle carries the lock 95 disk 11.

A safe as ordinarily placed upon the market, is equipped with a lock, embodying a casing and tumblers, which is mounted at the inner end of the sleeve 9, and the tumblers are manipulated by the spindle. The tumblers of course control the operation of the bolts.

In accordance with the present invention, I provide a support, preferably embodying 100 a pair of brackets 12. I may mount one of these pairs of brackets upon one side of the spindle, or I may mount two or more pairs, two pairs being shown for the purpose of illustration. The brackets 12 are provided at their ends adjacent the plate 6 with horizontal portions 13, which are secured to the plate 6 by bolts or machine screws 14. It is obvious that it will be necessary to drill holes in the plate 6, for securing the brackets thereto, and it will also be seen that these brackets may be located at any desired se- 105 110

lected position, with respect to the sleeve 9. In making a new safe, these brackets may be cast integral with the plate 6.

The ordinary or standard lock supplied by the manufacturer, with the safe, is shown as mounted upon the brackets 12, this lock having been purposely removed from its position adjacent the sleeve 9, where it was attached to the plate 6 by screws or the like. This lock embodies a casing 15, provided with a centrally arranged tube or sleeve 15'. Arranged within this casing are a plurality of tumblers 16, rotatable upon the sleeve 15', and an operating element or cam 17. The operating element or cam 17 is internally screw-threaded to receive the reduced screw-threaded end 18 of the spindle, upon which it is adapted to be keyed. The reduced screw-threaded portion 18 is adapted to rotate within the sleeve 15', but has no screw threaded engagement therewith. When the lock is removed from proximity to the sleeve 9 and mounted upon the brackets 12, the sleeve 15' rotatably receives the spindle 20, which is screw-threaded at its outer end for engagement with the operating element 17, and this spindle has a groove 21, corresponding to the groove 39, for the reception of the key. The spindle 20 is provided at its end adjacent the plate 6 with a bevel gear 22, preferably formed integral therewith. In the present instance, I have shown two locks 15, one of these locks being removed from the ordinary position, and the second lock being of similar construction, which may be readily obtained in the market. The invention is in no sense restricted to the use of any particular number of locks, as satisfactory results are obtainable by using only one lock, but the number may be widely varied, as found advantageous.

The bevel gears 22 are engaged by bevel gears 23, which are longitudinally adjustably mounted upon the operating shafts 24. These shafts have their outer ends screw-threaded, at 25, for engaging within screw-threaded openings formed in the hubs of the bevel gears 23. The screw-threaded ends 25 are provided with grooves 26, for receiving keys 27, also fitting in grooves formed in the bevel gears. It is thus seen that the bevel gears 23 may be rotated and thereby longitudinally adjusted upon the shafts 24, and subsequently locked in adjustment thereto, by means of the keys 27. The screw-threaded portions 25 of these shafts rotate within openings 28, which have smooth walls, and hence there is no screw-threaded engagement between these parts.

At the inner ends of the shafts 24 I provide brackets 29, having openings 30, which rotatably receive the screw-threaded inner ends 31 of the shafts 24. The walls of these openings are smooth and hence there is no screw-threaded engagement between the

parts. A ring 31 has screw-threaded engagement with the inner end of each shaft 24, and is locked thereon by a clamp or bolt 32 or the like. The brackets 29 are separate from the plate 6 and are secured thereto by machine screws 33 or the like. The brackets 29 may be cast integral with the plate 6, when making a new safe, if desired. Bevel gears 34 have screw-threaded openings, for receiving the screw-threaded inner ends of the rods 24, and these bevel gears are held against turning movement upon the rods by keys 35, inserted in grooves 36 in the shafts 24, and in the bevel gears.

Arranged between the bevel gears 34 is a bevel gear 37, engaging therewith. This bevel gear has a screw-threaded opening for receiving the reduced portion 18 of the spindle. The gear 37 is held upon this reduced portion 18 against turning movement, by a key 38, fitting in a groove 39, formed in the reduced portion 18, and in a groove in the bevel gear. It is preferred that the inner end of the spindle 10 be screw-threaded, as shown at 40, for receiving a ring 41, internally screw-threaded, which ring may be clamped to the spindle by a set screw 42 or the like.

In view of the foregoing description it will be seen, that the lock dial 11 is turned in the usual manner, for turning the spindle 10, and this turning movement will turn the shafts 24. The shafts will rotate the operating cams or elements 17, which in turn will manipulate the tumblers 16. If a burglar should drive the spindle 10 inwardly, out of the sleeve 9, it is obvious that the locks 15 would not be disturbed, and hence the door would not open.

In view of the foregoing description it is obvious that I have provided a construction which is in the nature of an attachment, and may be applied to almost any make of safe, for supporting the lock contained therein, at a point remote from the spindle, without materially altering the construction of the lock or other parts of the safe.

It is to be understood that the form of my invention herewith shown and described is to be taken as a preferred embodiment of my invention, and that various changes in the shape, size, and arrangement of parts may be resorted to without departing from the spirit of my invention or the scope of the subjoined claims.

Having thus described my invention, I claim:

1. The combination with a safe door provided with a rotatable spindle having a screw threaded end portion, of a support separate from the door and detachably mounted thereon at a point remote from the spindle, a shaft carried by the support, a gear mounted upon the inner end of the shaft, a gear having a screw threaded open-

ing for receiving the screw threaded portion of the spindle and engaging the first named gear, a lock casing mounted upon said support, rotatable elements held within the lock casing and having their planes of rotation substantially parallel with the plane of the door, one element serving as a driving element and having a screw threaded opening, an auxiliary spindle mounted within the lock casing and having a screw threaded portion of the same diameter as the screw threaded portion of the first named spindle whereby the auxiliary spindle may be employed to operate the driving element of the lock, a gear mounted upon said shaft, and a gear mounted upon the auxiliary spindle and engaging the last named gear.

2. The combination with a safe door provided with a rotatable spindle, of a support mounted upon the door at a point remote from the spindle and having an opening formed therein, a shaft having a screw threaded portion which is provided with a longitudinal groove, said shaft being rotatably mounted within the support, a gear having a screw threaded opening and mounted upon the screw threaded portion of the shaft to be longitudinally adjustable thereon, a key for insertion within the groove to lock the gear to the shaft for rotation therewith, a lock casing mounted upon the support, rotatable elements held within the lock casing and having their planes of rotation parallel with the plane of the door, one element serving as a driving element, a spindle engaging the driving element, a gear carried by the last named spindle and engaging said gear, a gear mounted upon the inner end of said shaft, and a gear mounted upon the first named spindle and engaging the last named gear.

3. The combination with a safe door provided with a rotatable spindle extending transversely through the same, of a support mounted upon the inner side of the door remote from the spindle, a lock casing mounted upon said support, rotatable elements held within the lock casing and having their planes of rotation substantially parallel with the plane of the door, one element serving as a driving element and having an opening formed therein, an auxiliary spindle mounted within the lock casing and having a portion of the same diameter as the corresponding portion of the said spindle whereby the auxiliary spindle may be inserted within the opening of the driving element of the lock, a gear mounted upon the first named spindle, a gear mounted upon the auxiliary spindle, and driving means between said gears.

4. The combination with a safe door provided with a rotatable spindle, of a lock casing mounted upon the door at a point remote from said spindle, rotatable elements held within the lock casing and having their planes of rotation substantially parallel with the plane of the door, one element serving as a driving element, a spindle engaging the driving element, a gear carried by the last named spindle, a shaft extending between the first and second named spindles, a gear mounted upon the shaft for engagement with the first named gear, means whereby the gear upon the shaft may be longitudinally adjusted and locked to the shaft in a selected adjusted position, a gear mounted upon the first named spindle, and a gear mounted upon said shaft and engaging the gear of the first named spindle. 80

In testimony whereof I affix my signature.
NORMAN E. DONOHUE.
